UNITED STATES PATENT OFFICE.

LESLIE R. McDONALD, OF MONTREAL, QUEBEC, CANADA.

ADVERTISEMENT-DISPLAYING MECHANISM.

Application filed December 21, 1922. Serial No. 608,208.

To all whom it may concern:

Be it known that I, LESLIE R. McDONALD, a citizen of the United States, residing at Montreal, Province of Quebec, Dominion of Canada, have invented certain new and useful Improvements in Advertisement-Displaying Mechanisms, of which the following is a specification.

My invention relates to that class of advertisement displaying mechanisms wherein a plurality or series of display elements, such as flexible sheets, are wound upon a drum or carrier and are released one by one so as to drop into view position in a suitable exhibition space; and my improvements are directed particularly to means whereby the carrier shall be moved step by step as the sheets are released; and to means whereby the dropping of the sheets may be accelerated; and also to means whereby the fronts and backs of the several sheets may be used for exhibition purposes, such as the display of advertisements and the like; all of which, together with various details of adjustment and construction, I will now proceed to explain, referring in so doing to the drawings, in which Fig. 1 is a vertical sectional view taken on the line 1—1 of Fig. 3, looking to the left; Fig. 2 is a similar view taken on the line 2—2 of Fig. 3, looking to the right, a portion of the framework near the bottom being broken away to show the construction more clearly; Fig. 3 is a rear elevation with the back of the case removed; Fig. 4 is a front elevation showing the arrangement of the advertisements; Fig. 5 is an end view of the placard roller, sheet release roller and adjacent parts; Fig. 6 is a top view of the sheet release roller and a series of sheet ends; Figs. 7 and 8 are, respectively, side elevation and plan views of the drum turning and holding pawls; Fig. 9 is a detailed part of the sheet releasing mechanism and Fig. 10 is a plan view of the end of the blower pipe; Figs. 5, 6, 7, 8 and 9 are on a much enlarged scale as compared with the other figures.

The same parts are designated by corresponding reference numerals in all the figures.

The apparatus is preferably mounted in a suitable casing or box 2, provided with supporting bars as 3, 4, carrying plates 5, 6, in which are journalled the ends of the shaft 7, which carries the placard drum 8, upon which the series of placards 9, 9, 9, are wound.

An electric motor 10 is mounted in the apparatus, as by being attached, through intermediate means such as a hanger 11, to the support 3, the motor being preferably adjustably secured to the hanger, as by a clamping screw 12, so as to allow for its adjustment in aligning its shaft 13, which is preferably flexible and drives a shaft 14 carrying a blower fan 15, which impels a current of air up through a preferably flexible conduit 16 and discharges the air through ports 17, 17 at points on either side of a sheet releasing roller.

An electric motor is preferably placed in a circuit including a variable resistance 27.

The shaft 14 carries a worm 18 which gears with the worm gear 19, carried on a shaft 20 journalled in an extension of the carrying plate 5. The shaft 20 is provided with a head 21, a collar 22 and a fixed cam 23. Upon this cam 23 is mounted a retracting pawl arm 24; a detent pawl arm 25 is also mounted on the shaft 20.

A spring washer 26, or a similar take-up element, is interposed between the head 21 and the hub of the pawl arm 25, and the collar 22 is pressed firmly against the pawl arm 24, so that the rotation of the shaft 20 will tend to swing the pawl arms bodily around with it, but this will be prevented by the slipping of the shaft within the hubs of the arms. This frictional arrangement serves, when the shaft is rotated anti-clockwise, to hold the ends of the pawl arms normally in engagement with the teeth of a wheel 30, which is fixed upon the shaft 7, the rotation of the cam 23 serving to push forward and retract the arm 24 once with each revolution of the shaft 20, thereby moving the wheel 30 one step clockwise, with each revolution of the shaft 20, the arm 25 yielding to allow each tooth to pass it and then acting as a detent pawl.

Upon the shaft 7 is fixed a worm gear 31 meshing with a worm 32 on a shaft 33, mounted in bearings in a bracket 34, carried adjustably, by means of pivot pin 35 set into 5 a plate 36, and by a set screw 37 passing through a slot 38 in the plate 36, so that the bracket 34 may be swung up and down on its pivot 35 and locked in a preferred position.

The end of the shaft 7 passes through the 10 plate 36, which is adjustably secured to the standard 5 by means of set screws 39 and 40, the set screw 40 passing through a curved slot in the plate 36, and the head of the set screw 39 engaging over the curved end of 15 the plate 36; so that the plate 36 can be swung on the shaft 7 as a pivot, to permit desired adjustment.

On the shaft 33 is mounted a worm 44 which meshes with a worm gear 45 mounted 20 on a shaft 46, one end of which shaft is journaled in one of a series of sockets 47, 47, in a block 48 slidably secured to the bracket 34 by means of a set screw 49 passing through a slot in the bracket. The 25 other end of the shaft 46 is provided with a socket in which is inserted the pivot pin 53, carried by an arm 54 pivoted by a bolt 55 to a bracket 56 through which the end of the shaft 7 passes, the bracket 56 being 30 adjustably locked to the standard 6 by means of a set screw 57 passing through a curved slot in the bracket 56.

A coiled spring 58 normally tends to draw the arm 54 forward toward a placard 35 drum 9.

On the shaft 46 is mounted a roller 60, provided with two relatively, transversely disposed elliptical portions 61, 62, the outer 40 ends of which each represent an arc of substantially 90 degrees of a circle.

In the ends of the placard 9 are formed notches or recesses 65, 66; the recesses alternating in the sheets and forming a staggered row; one row, as 65, registering beneath the portion 61 of the roller 60, and the other series 66 registering beneath the portion 62 of the roller 60, so that, as the overlapped ends of the rolled placards travel under the roller 60, as the drum and 50 roller revolve, the ends of the placards will be alternately released by the opposite ends of the roller.

To the standards 5 and 6 respectively are secured arms 70 and 71, through which pass 55 the shaft 7, the arms being secured to the standards by means of set screws 72, 72 and 73, 73, passing through curved slots in the standards, so that the arms may be swung up and down and fastened in their desired 60 positions.

The free ends of the arms are slotted, and by suitable set screws 74 and 75 passing through the slots a cross bar 76 is secured between the arms. This cross bar supports 65 the flexible conduit 16, into the upper end

of which a slidable portion 06 is preferably inserted to allow for freedom of adjustment.

The cross bar 76 also carries suitable means, such as springs 77, 77, for keeping the placards snugly rolled around the drum.

In the top of the casing 2, above the placard drum, is a mirror 80, which is set at such an angle that an image from the top of the roller will be projected by the 75 mirror in the direction of the normal position of an observer standing or sitting before the casing.

Another mirror 81 is placed near the bottom of the casing at such an angle that an 80 image from the underside of the placard drum will be reflected from that mirror in the direction of an observer standing or sitting before the casing. Side mirrors 83 and 84 are also, preferably, mounted in the 85 casing.

The placards are designed to give the greatest prominence to what is shown upon their faces, which appear at the back of the cabinet when the placards are released and allowed to drop down, as indicated by the 90 broken lines in Fig. 2, and by 90 in Fig. 4.

However, the backs of the placards may also be utilized, as I have illustrated in Fig. 4. Thus upon that portion of the back of each 95 placard which is normally on the front of the drum when the preceding placard has been released, suitable matter may be displayed, as is indicated at 91, and this will be seen directly by an observer in front 100 of the apparatus.

On the part of the placard which is at the time mentioned exposed on top of the placard drum, other matter may be displayed, which, if it consists of lettering, should 105 preferably be arranged in reversed form, so that when its image is reflected by the mirror 80 the letters and words will appear in proper arrangement. For the purpose of illustration, the tops of such a series of reversed letters are indicated at 92 in Fig. 4, while their corrected reflections appear in the mirror 80 above.

Similarly, that part of the placard which is below the drum may also be used as a display space, the lettering, if employed, being here also reversed. The reflection of the display, from this portion of the placard will be seen in the mirror 81 at the bottom 115 of the casing. The position of the tops of a series of reversed letters is indicated at 93 in Fig. 4.

By this arrangement it is possible to use not only the greater part of the face of each placard for publicity purposes, but also to 120 use a substantially equal amount of the space on the back of each placard, thereby substantially doubling the amount of space which can be used for publicity purposes on any given number of placards, for 125 130

it is obvious that if both sides of the sheet are used, the efficiency of the apparatus is increased to the extent of such double use.

When the reflection from the placard at 5 the back of the apparatus is viewed from an angle at one side of the apparatus, the observer will obtain a view of a series of reflections and counterreflections thrown back and forth between the mirrors, some, of 10 course, showing the placard matter reversed and others in its correct form. This is calculated to attract the attention of passers-by and to lead to their further observation of the matter displayed by the apparatus.

15 The operation of my apparatus is as follows.

A suitable series of placards having been mounted and wound on the drum, the bar 20 properly against the rolled placards. The neck 06 of the air duct is adjusted to discharge the current of air against the ends of the sheets at each side of the roller 60. The position of the shaft 46 is adjusted so 25 that the portions 61 and 62 of the roller 60 will alternately engage the ends of the placards 9, a sheet holding elliptical portion 61 pressing on the sheet back of the notch beneath it, so as to hold that sheet fast when 30 the top sheet is released by the elliptical portion 62, and vice versa, the adjustment of the roller being facilitated because of the flexible support afforded by the arm 54, by swinging which the end of the shaft 46 35 may be released to permit adjustment of its other end.

Proper adjustments having been made, the motor 10 is put in motion, revolving the fan 15, and also through the worm 18, gear 19, shaft 20 and its attachments, actuating the pawl arm 24, so as to move the wheel 30 one tooth with each revolution of the shaft 20, the reverse movement of the wheel being prevented by the pawl 25. The wheel 30 turns 45 the shaft 7. And if the placards carried by the drum correspond in number with the teeth on the wheel 30, it is obvious that one placard may be released, as I will explain, for each tooth of the wheel 30 which 50 passes a given point. The turning of the shaft 7 rotates the wheel 30, which, through worms 32 and 44 and worm gear 45, turns the shaft 46 and rotates the roller 60, the various elements in the chain of transmission being so proportioned that the roller 62 makes a quarter turn for each tooth of the wheel 30 which passes a given point. Hence, when the pawl arm 24 turns the 55 wheel 30 one tooth space, the grip of the roller 60 upon the placards is changed from one end to the other of the roller, the top placard being released by one end of the roller while the next one is held by the other end of the roller, the notching of the ends of

the placards giving the roller ends double 65 space, instead of single space, holds against the placards.

When comparatively thin placards are wound closely upon a drum they may not always free themselves and drop forward 70 when their ends are released, as quickly as is desirable, but any tendency to hang back in this way is overcome by the current of air from the blower 15, which is discharged against the ends of the placards and which 75 at once blows the end of the placard forward and free as soon as it is released by the roller 60.

While the arm 44 is being thrust forward again by the shaft 20 and its cam, the placard drum and its attachments will remain 80 at rest, so that the placard announcements may be examined by any observer.

By this it will be understood that the form of apparatus which I have illustrated as embodying my invention is to be regarded as a typical structure only, for details of structure and arrangement can be modified by the use of mechanical equivalents and the like without departing from the spirit of 90 my invention and the scope of the claims.

Having thus described my invention, what I claim and desire to secure by Letters Patent of the United States is:—

1. In a display apparatus, the combination 95 of a rotatable placard carrier, a series of flexible placards, having free ends of the normal thickness of the placards rolled around the carrier, roll keepers and means for adjusting the roll keepers radially of 100 the carrier.

2. In a display apparatus, the combination 105 of a rotatable placard carrier, a series of flexible placards, having free ends of the normal thickness of the placards rolled around the carrier, roll keepers and means for adjusting the roll keepers circumferentially of the carrier.

3. In a display apparatus, the combination 110 of a rotatable placard carrier, a series of flexible placards, having free ends of the normal thickness of the placards rolled around the carrier, roll keepers and means for adjusting the roll keepers radially and circumferentially of the carrier.

4. In a display apparatus, the combination 120 of a rotatable placard carrier, a series of flexible placards, having free ends of the normal thickness of the placards each attached by one end to and wound around the carrier, and rotatable means for releasing the free ends of the placards successively.

5. In a display apparatus, the combination 125 of a rotatable placard carrier, a series of flexible placards, having free ends of the normal thickness of the placards each attached by one end to and wound around

- the carrier, carrier rotating means, and rotatable means for releasing the free ends of the placards successively.
6. In a display apparatus, the combination of a rotatable placard carrier, a series of flexible placards, having free ends of the normal thickness of the placards each attached by one end to and wound around the carrier, carrier rotating means, and rotatable means, actuated by the carrier rotating means, for releasing the free ends of the placards successively.
7. In a display apparatus, the combination of a rotatably placard carrier, flexible placards rolled on the carrier and provided with indentations in their free ends laterally staggered in successive placards, carrier rotating means, and rotatable means, actuated by the carrier rotating means, registering alternately over an indenture or against a placard end, for releasing the free ends of the placards one by one.
8. In a display apparatus, the combination of a rotatable placard carrier, flexible placards rolled on the carrier and provided with notches in their free ends laterally staggered in successive placards, and rotatable means having a plurality of sheet holding elements arranged in staggered relation around said rotatable means, said sheet holding elements registering with said notches.
9. In a display apparatus, the combination of a rotatable placard carrier, flexible placards rolled on the carrier and provided with notches in their free ends laterally staggered in successive placards, carrier rotating means, and rotatable means, actuated by the carrier rotating means, having a plurality of sheet holding elements arranged in staggered relation around said rotatable means, said sheet holding elements registering with said notches.
10. In a display apparatus, the combination of a rotatable placard carrier, flexible placards rolled on the carrier and provided with notches in their free ends laterally staggered in successive placards, and rotatable means embodying a plurality of alternating operating sheet holding elements arranged in staggered relation around said rotatable means, said sheet holding elements registering with said notches.
11. In a display apparatus, the combination of a rotatable placard carrier, flexible placards rolled on the carrier and provided with notches in their free ends laterally staggered in successive placards, and rotatable means embodying a plurality of elongated and relatively transversely disposed sheet holding elements arranged in staggered relation around said rotatable means, said sheet holding elements registering with said notches.
12. In a display apparatus, the combination of a rotatable placard carrier, a series of flexible placards each secured thereto by one end and rolled thereon, and having a free end of the normal thickness of the placard rotatable means for releasing free ends of the placards one by one, and means for adjusting said releasing means, radially of the placard carrier.
13. In a display apparatus, the combination of a rotatable placard carrier, a series of flexible placards each secured thereto by one end and rolled thereon, and having a free end of the normal thickness of the placard rotatable means for releasing free ends of the placards one by one, and means for adjusting said releasing means circumferentially of the placard carrier.
14. In a display apparatus, the combination of a rotatable placard carrier, a series of flexible placards each secured thereto by one end and rolled thereon, and having a free end of the normal thickness of the placard rotatable means for releasing free ends of the placards one by one, and means for adjusting said releasing means radially and circumferentially of the placard carrier.
15. In a display apparatus, the combination of a rotatable placard carrier, a series of flexible placards rolled thereon, and each having a free end of the normal thickness of the placard carrier rotating means, rotatable means for releasing free ends of the placards one by one, transmission means, actuated by the carrier rotating means, for rotating the releasing means, and means for optionally causing relative adjustment of the actuating means and the transmission means.
16. In a display apparatus, the combination of a rotatable placard carrier, a series of flexible placards rolled thereon, and each having a free end of the normal thickness of the placard carrier rotating means, rotatable means for releasing free ends of the placards one by one, transmission means, actuated by the carrier rotating means, for rotating the releasing means, and means for optionally causing relative adjustment of the actuating means and the transmission means circumferentially of the placard carrier.
17. In a display apparatus, the combination of a rotatable placard carrier, a series of flexible placards rolled thereon, and each having a free end of the normal thickness of the placard carrier rotating means, rotatable means for releasing free ends of the placards one by one, transmission means, actuated by the carrier rotating means, for rotating the releasing means, and means for optionally causing relative adjustment of the actuating means and the transmission means radially of the placard carrier.
18. In a display apparatus, the combination of a rotatable placard carrier, a series

of flexible placards rolled thereon, and each having a free end of the normal thickness of the placard carrier rotating means, rotatable means for releasing free ends of the 5 placards one by one, transmission means, actuated by the carrier rotating means, for rotating the releasing means, and means for optionally causing relative adjustment of the actuating means and the transmission 10 means circumferentially and radially of the placard carrier.

19. In a display apparatus, the combination of a rotatable placard carrier, a series 15 of flexible placards rolled thereon, carrier rotating means, rotatable means for releasing free ends of the placards one by one, transmission means, actuated by the carrier rotating means, for rotating the releasing means, and means, embodying a worm and 20 a relatively shiftable worm gear, for optionally causing relative adjustment of the actuating means and the transmission means.

20. In a display apparatus, the combination of a rotatable placard carrier, a series 25 of flexible placards rolled thereon, carrier rotating means, rotatable means for releasing free ends of the placards one by one, transmission means, actuated by the carrier rotating means, for rotating the releasing 30 means, and means, embodying worms and relatively shiftable worm gears, for optionally causing relative adjustment of the actuating means and the transmission means.

21. In a display apparatus, the combination 35 with a rotatable placard carrier, of means for rotating the carrier step by step, embodying a ratchet wheel, a rotating shaft provided with an eccentric cam, a retractable and projectable pawl arm carried by 40 said cam, a detent pawl mounted on said shaft, and frictional, coordinating means.

22. In step by step actuating means, the combination of a rotatable shaft provided 45 with an eccentric cam, a retractable and projectable arm mounted on the cam, a detent arm mounted on the shaft, and means for frictionally coordinating the relative movements of the shaft and arms.

23. In step by step actuating means, the 50 combination of a rotatable shaft provided with an eccentric cam, a retractable and projectable arm mounted on the cam, a detent arm mounted on the shaft, and means embracing a spring washer for frictionally 55 coordinating the relative movements of the shaft and arms.

24. In step by step actuating means, the combination of rotatable means, projectable and retractable means carried and actuated thereby, detent means carried by the 60 rotatable means, and means for producing frictional correlation between the shaft and arms.

25. In a display apparatus, the combination 65 of a rotatable placard carrier provided

with a series of flexible placards each attached thereto by one end and rolled thereupon, rotatable means for releasing the free ends of the placards one by one, means for definitely separating each freed end from 70 the roll as released, means for rotating the placard carrier step by step, and common means for actuating the said carrier rotating means, releasing means and separating 75 means.

26. In a display apparatus, the combination of a rotatable placard carrier provided with a series of flexible placards each attached thereto by one end and rolled thereupon, rotatable means for releasing the free 80 ends of the placards one by one, means for definitely separating each freed end from the roll as released, means for rotating the placard carrier step by step, and common means, embodying an electric motor, for actuating the said carrier rotating means, releasing means and separating means.

27. In a display apparatus, the combination, in a casing, of a rotatable placard carrier, a flexible placard carried thereby and 90 provided with direct display matter upon one side and with reversed matter and direct display matter upon its other side, and reflecting means for rectifying and displaying 95 such reversed matter.

28. In a display apparatus, the combination, of a rotatable placard carrier, a flexible placard carried thereby and provided with direct display matter upon one side, 100 and upon its other side with reversed matter at two points separated by direct display matter, and reflecting means for rectifying and displaying such reversed matter.

29. In a display apparatus, the combination, of a rotatable placard carrier, a roll 105 of flexible placards carried thereby, each placard being provided with direct display matter upon its face, and upon its back with direct display matter and with a plurality of sections of reversed matter, means for displaying the face of one placard in plane, and simultaneously displaying the direct matter upon the back of the succeeding placard, and reflecting means for simultaneously displaying the reversed matter 110 upon said back in rectified form.

30. In a display apparatus, the combination, of a rotatable placard carrier, a roll 120 of flexible placards carried thereby, each placard being provided upon its face with direct display matter and upon its back with reversed matter, reflecting means for rectifying and displaying such reversed matter, and laterally disposed, mutually opposed reflecting means for producing a series of 125 images of the face of the placard.

31. In a display apparatus, the combination of placard holding means, placards provided with display matter upon both 130 sides, means for displaying the face of one

placard directly and in a plurality of reflected series, and means for simultaneously displaying part of the back of another placard directly and another part indirectly by reflection.

32. In a display apparatus, the combination of placard holding means, placards provided with display matter upon both sides,

means for displaying the face of one placard directly and in a plurality of reflected series, and means for simultaneously displaying part of the back of another placard directly and other parts indirectly by reflection.

LESLIE R. McDONALD.
